US00D968402S

(12) **United States Design Patent** (10) Patent No.: **US D968,402 S**
(45) Date of Patent: ** *Nov. 1, 2022

(54) **HEADSET STRAP**

- (71) Applicant: **META PLATFORMS TECHNOLOGIES, LLC**, Menlo Park, CA (US)
- (72) Inventors: **Enric Vial Roig**, Seattle, WA (US); **Mauricio Romano**, Redmond, WA (US); **David Michael Pickett**, Seattle, WA (US); **Peter Allan Chase Newbury**, Burlington, WA (US); **Quintin Morris**, Seattle, WA (US); **Peter Wesley Bristol**, Seattle, WA (US); **Joseph Patrick Sullivan**, Seattle, WA (US); **Glen Jason Tompkins**, Woodinville, WA (US); **Joel Bernard Jacobs**, Seattle, WA (US)
- (73) Assignee: **Meta Platforms Technologies, LLC**, Menlo Park, CA (US)

(*) Notice: This patent is subject to a terminal disclaimer.

(**) Term: **15 Years**

(21) Appl. No.: **29/754,281**

(22) Filed: **Oct. 8, 2020**

CLAIM

The ornamental design for a headset strap, as shown and described.

DESCRIPTION

FIG. 1 is a front perspective view of a headset strap showing the claimed design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

(Continued)

The broken lines shown in the figures illustrate portions of the headset strap that form no part of the claimed design.

1 Claim, 7 Drawing Sheets
